MATRIX MOLDING MACHINE

Hobart N. Durham, Manhasset, N. Y., assignor to
 The Goss Printing Press Company, Chicago,
 Ill., a corporation of Illinois

Application March 9, 1936, Serial No. 67,810

4 Claims. (Cl. 60—52)

The present invention relates to matrix molding presses and more particularly to a hydraulically operated matrix press particularly suited for the production of stereotype matrices.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, constructions, arrangements, combinations and improvements herein shown and described.

15 The accompanying drawing, referred to herein and constituting a part hereof, illustrates one embodiment of the invention, and together with the description, serves to explain the principles of the invention.

20 The single figure of the drawing shows an illustrative embodiment of the invention and is largely diagrammatic.

The present invention has for its object the provision of a novel and improved hydraulic matrix molding press. A further object of the invention is the provision of a molding press for the production of stereotype matrices, which press does not require constant attention on the part of the operator and insures the production 30 of matrices of uniformly high quality. Still another object of the invention is the provision of a hydraulic matrix molding press in which the hydraulic pressure for operating the press is produced centrifugally.

35 Referring to the illustrative embodiment of the invention, there is provided a hydraulic matrix molding press, a motor driven centrifugal pump for supplying liquid to said press at the requisite high pressure, and motor control means 40 for starting, stopping and controlling the speed of the motor so as to govern the action of the hydraulic press. Means are also provided for controlling the flow of liquid to and from the pump and press and these means are preferably 45 interconnected with the motor control means so that only a single control need be operated by the operator. The motor speed control means are preferably automatically controlled by means of the pressure so that a predetermined pressure is exerted on the flong by the press, after which the pressure is reduced and maintained at its reduced value so long as is necessary for the complete molding of the matrix.

It will be understood that the foregoing general description and the following detailed de-

scription as well are exemplary and explanatory of the invention but are not restrictive thereof.

Referring now in detail to the illustrative embodiment of the invention, there is provided a hydraulic matrix molding press which comprises the frame 10, a stationary or upper platen 11 against which the pressure is exerted, a moving platen 12 mounted on the upper end of the hydraulic plunger 13 which extends into the pressure chamber 14 formed as a part of the lower portion of frame 10. A liquid passageway 15 also extends through the frame and connects the chamber 14 alternatively with the sump 16 or high pressure centrifugal pump 17 through the three-way valve 20.

15 The means for rapidly creating the predetermined high pressure comprises a multi-stage centrifugal pump 17 driven by motor 22 and having an intake pipe 23 and an outlet pipe 24, and is adapted to develop extremely high pressures, the exact amount of pressure being a function of the speed at which the motor 22 drives the pump, and by regulating the speed of the motor substantially any desired liquid pressure may be produced.

20 Power is supplied to motor 22 from mains 25 and 26 through switch 27 which is mechanically interconnected with valve 20 so that with the valve in draining position, the switch is opened to stop the pump, while with the valve in operating position, the motor is supplied with power.

25 Means are provided for varying the speed of the motor, and for this purpose an alternatively usable resistance 30 may be placed in series with the motor 22 so as to reduce the speed of the motor, thereby reducing the pressure developed by the pump 17, but maintaining sufficient pressure to hold the platens 11 and 12 in matrix drying position. Automatic means may be provided for automatically reducing the pressure 30 developed by the pump 17, and preferably these means are adapted to effect this reduction in motor speed and developed pressure immediately that the maximum desired pressure has been developed by the pump.

35 As embodied, a pressure indicator 32 is connected to the pressure chamber 14 of the matrix press, and this pressure indicator is provided with a variably positionable contact 33 closing a circuit when the maximum desired pressure has 40 been attained within the chamber. A polarized relay 35 is provided which is alternatively adapted to place the resistance 30 in series with the motor windings or to connect the motor directly to the supply mains. The variably positionable

contact 33 is adapted to place one of the coils of the polarized relay 35 in circuit and thereby place the resistance 30 in the motor circuit, while another contact 51 is provided on the main switch and is closed during movement of the valve 20 from one of its positions to another to energize the other coil of the polarized relay and restore the motor circuit to normal or full speed condition.

10 The various electrical parts of the present embodiment are illustratively shown connected as follows:

One of the mains 25 is directly connected to the motor, while the other main 26 is also connected to the motor 22 through contact segment 41, switch bar 42, contact 43, armature 44, contact 45 or alternative contact 46 and resistance 30.

15 The magnet 50 of polarized relay 35 is connected to mains 25 and 26 through contact segment 41, bar 42, contact 43, pressure operated contact bar 51 and variably positionable contact 33.

20 The magnet 55 of polarized relay 35 is connected to mains 25 and 26 through contact segment 41, switch bar 42, and contact 51, so that as valve 20 is moved from open to closed position, or vice versa, contact 51 is placed in circuit to energize magnet 55 and reset the polarized relay to high speed position.

25 In the operation of the illustrative embodiment, the operator positions the form 60 on the movable platen 12, places the flong 61 over it together with the necessary blankets 62, and moves the switch and valve controlling lever to full pressure position. This movement of the valve, first closes the circuit through contact 57 to energize the windings of magnet 55 and positions the armature 44 in high speed position. Upon completion of the valve movement, power is supplied to the motor 22 through contacts 45 and 43, starting the motor 22 and supplying liquid under pressure to the pressure chamber 14 to move platen 12 upwardly and force the flong 61 into the depressions of the form 60.

30 The discharge of liquid from the centrifugal pump is extremely rapid at first, gradually diminishing as the resistance to this flow is increased and finally ceasing when the pressure exerted between the platens balances the pressure created by the pump. Thus, the platen 12 moves rapidly at first until pressure is exerted on the flong and form and then the flow is gradually diminished, slowly pressing the flong into the form and stopping when the pressure exerted on the flong balances the maximum pressure which can be created by the pump at the speed at which it is operated.

35 The maximum pressure to be developed by the pump and thereby the maximum pressure to be developed between the platens 11 and 12 is variably limited, and for this purpose the pressure indicator 32 is provided with a variably positionable contact 33 which automatically reduces the motor speed when the maximum desired pressure has been attained. This reduced motor speed is sufficient to hold the flong against shrinkage during drying, but is not sufficient to prevent rapid drying in the usual manner. Upon contact of indicator arm 51 with contact 33, current is supplied to the windings of magnet 50 throwing armature 44 into contact with contact 46 and thereby placing the resistance 30 in series with the motor windings. As the pressure created by

the pump 17 is substantially proportional to the square of the speed of motor 22, only a small reduction in motor speed is necessary to effect a relatively large reduction in maximum pressure between the platens 11 and 12.

40 After the flong has dried sufficiently, the valve 28 is restored to its draining position, as shown, resetting the armature 44 by energization of magnet 55, and the liquid drains from the pressure chamber 14 into the sump 16, allowing the platen 12 to descend and thereby permitting easy removal of the matrix and form.

45 The invention in its broader aspects is not limited to the specific mechanisms shown and described but departures may be made therefrom within the scope of the accompanying claims without departing from the principles of the invention and without sacrificing its chief advantages.

50 What I claim is:

1. A matrix molding press including in combination relatively movable platens, a hydraulic plunger for moving one of the platens, a high-pressure centrifugal pump for supplying liquid to said plunger, means for driving said pump at a plurality of different speeds, a polarized relay for controlling the driving speed, and means operated by the pump pressure for controlling said relay to reduce the motor speed and pump pressure after a maximum pressure has been reached.

55 2. A matrix molding press including in combination relatively movable platens, a hydraulic plunger for moving one of the platens, a high-pressure centrifugal pump for supplying liquid to said plunger, motor means for driving said pump at a plurality of different speeds, a polarized relay for controlling the motor speed and means operated by a variably predetermined pump pressure for controlling said relay to reduce the motor speed when the pressure has attained a predetermined maximum whereby the liquid supplied to the plunger by the pump is at a lower than maximum pressure.

60 3. A matrix molding press including in combination relatively movable platens, a cylinder in which is a hydraulic plunger for moving one of the platens, a high-pressure centrifugal pump for supplying liquid to said plunger, motor means for driving said pump at a plurality of different speeds, a relay for controlling the motor speed, means operated by the pressure applied to the plunger for actuating said relay to reduce motor speed, a drain valve for draining the cylinder, a motor switch through which power is supplied to the pump motor and a common means for opening said valve and switch and for closing said valve and switch.

65 4. A matrix molding press including in combination relatively movable platens, a cylinder in which is a hydraulic plunger for moving one of the platens, a high-pressure centrifugal pump for supplying liquid to said plunger, motor means for driving said pump at a plurality of different speeds, a relay for controlling the motor speed, means operated by the pressure applied to the plunger for actuating said relay to reduce motor speed, a drain valve for draining the cylinder, a motor switch through which power is supplied to the pump motor and a common means for opening said valve and switch and for closing said valve and switch, said switch also serving to reset said relay to its normal high-speed position.

70 HOBART N. DURHAM.
